UNITED STATES PATENT OFFICE.

NED E. BARNES, OF HOUSTON, TEXAS, ASSIGNOR OF FIFTY-ONE ONE-HUNDREDTHS TO
W. G. TWYMAN, OF HOUSTON, TEXAS.

TIE-PLATE.

1,180,467.

Specification of Letters Patent. Patented Apr. 25, 1916.

Application filed September 27, 1915. Serial No. 52,814.

To all whom it may concern:

Be it known that I, NED E. BARNES, a citizen of the United States, residing at Houston, in the county of Harris and State 5 of Texas, have invented certain new and useful Improvements in Tie-Plates, of which the following is a specification.

This invention relates to new and useful improvements in tie plates.

10 The object of the invention is to provide a plate of the character described, designed to be fastened upon the ties of a railway track to receive the rails and which will prevent said rails from wearing into the ties and from spreading or overturning.

15 With the above and other objects in view, the invention has particular relation to certain novel features of construction, operation and arrangement of plates an example 20 of which is given in this specification and illustrated in the accompanying drawings, wherein:

Figure 1 shows a plan view of the plate, Fig. 2 shows an edge view thereof, Fig. 3 25 shows an end view thereof, Fig. 4 shows a side view of a rail held in position by the plate, and Fig. 5 shows an isometric view thereof.

30 Referring now more particularly to the drawings, wherein like numerals of reference designate similar parts in each of the figures, the numeral 1 refers to the tie and the numeral 2 to the rail mounted thereon. The plate 3 is mounted upon the tie and 35 forms a seat which receives the rail. The underside of the plate has projecting teeth, 4 which engage with the tie and hold the plate in position while the rail is being placed thereon and spiked, as hereinafter 40 explained. The edges of the plate project each way beyond the rail base and the outer edge is divided, one section being upturned and resting against the outer side of the rail web and conforming to the contour of 45 the outer side of the rail, forming the knuckle 5, which prevents the rails from spreading or overturning. The plate is secured to the tie by two inner and one outer spike, 6 and 7 of the ordinary form which 50 through orifices in the plate and into the tie underneath and the enlarged heads of which engage over the edges of the corresponding rail, to hold said plate and rail in position.

What I claim is:

1. The combination with a railway rail 55 of a tie, a plate supported upon the tie, supporting the rail and projecting beyond each side of said rail, one of the outer edges of said plate being divided into sections, one of which sections is upturned and conforming in shape to the rail and resting against the outer side of the rail forming a brace for the base, web and ball thereof, and a plurality of spikes passing through one end 60 of the plate and a securing means passing through one section of the other end thereof, securing the plate and rail to the tie.

2. The combination with a railway rail 70 of a tie, a plate supported upon the tie, supporting the rail and projecting beyond each side of said rail, one of the outer edges of said plate being divided into sections, one of which sections is upturned and conforming in shape to the rail and resting against 75 the outer side of the rail forming a brace for the base, web and ball thereof, and a plurality of spikes passing through one end of the plate and a securing means passing through one section of the other end thereof, 80 securing the plate and rail to the tie, and a plurality of teeth integral with the plate adapted to bite into said tie.

3. The combination with a railway rail 85 of a tie, a plate supported upon the tie supporting the rail and projecting beyond each side of said rail, one of the outer edges of said plate being bifurcated, one of which sections is upturned and conforming in 90 shape to the rail and resting against the outer side of the rail forming a brace for the base, web and ball thereof, said plate having a plurality of openings passing therethrough, a plurality of spikes passing through the plate near the ends thereof 95 securing said plate and rail to the tie and a plurality of teeth integral with the plate and projecting downwardly therefrom adapted to bite into the tie to prevent the same from moving relative to the tie. 100

In testimony whereof I have signed my name to this specification in the presence of two subscribing witnesses.

NED E. BARNES.
